UNITED STATES PATENT OFFICE.

GEORGE HILLARD BENJAMIN, OF NEW YORK, N. Y.

SYSTEM OF AUTOMATIC BLOCK-SIGNALING FOR ELECTRIC RAILROADS.

1,163,063.

Specification of Letters Patent.

Patented Dec. 7, 1915.

Application filed April 3, 1911. Serial No. 618,537.

To all whom it may concern:

Be it known that I, GEORGE HILLARD BENJAMIN, a citizen of the United States, residing at the city, county, and State of New York, have invented certain new and useful Improvements in Systems of Automatic Block-Signaling for Electric Railroads, of which the following is a specification.

My invention relates to a system of automatic block signaling for electric railroads, and consists primarily in the means employed for connecting the signal controlling devices in the track circuits, and secondarily in the means employed for obtaining signal indications upon short blocks, the object of my invention being to improve and simplify such systems.

The accompanying diagrams will serve to illustrate my invention.

Figure 1 is a general view, illustrating a system in which the traffic rails are continuous and the signaling devices arranged to be controlled by cumulative drops of potential taken along two separate rails. Fig. 2 is a general view showing the same general system and illustrating a method of connecting and energizing short blocks.

Referring to the drawings; 5 indicates propulsion generator, shown in Fig. 1 as a direct current generator and in Fig. 2 as an alternating current generator; 6, feeder; 7-8 traffic rails. In Fig. 1 the rails 7-8 are continuous and are divided into blocks A, B, C, by means of crossbonds 9. In Fig. 2 the rails 7-8 are shown as divided by insulation 10 at the ends of a block section. Such division of the rails, however, only applies to that portion of the trackway where a short block or a plurality of short blocks are introduced.

In Fig. 2, D indicates short blocks; E, a block intervening between two short blocks D; and F, a block having the general characteristics, so far as continuity of the rails, etc., is concerned, of blocks A, B, C, of Fig. 1. The short blocks D are each provided with an additional conductor 11 for the propulsion current, and it will be observed that the rail 8 and conductor 11 are connected through a conductor 12 to the central point of a bond 9, and further, that by means of the conductor 11, which may have the same resistance and reactance per foot as the rail 7, the resistance and reactance presented to the propulsion current in blocks D is the same as would be presented in a

block similar to A, B or C of corresponding length. In the blocks D the divisional rail 7 transmits no propulsion current, its place being taken by the conductor 11. It will be further observed that in the blocks D no crossbonds 9 are used, and that the sections of rail 8 and conductor 11 are connected as before stated, through the conductor 12 to the central points of bonds 9 of the adjacent sections, as for instance E and F.

By the arrangement above described, short blocks can be introduced anywhere along the line or in yards, without in any wise interfering with the free passage of the propulsion current.

15 indicates signaling generator; 16-17, feeders; 20, energy transformer, having its primary 21 connected across the feeders 16-17, and its secondary 22 connected across the rails.

In the blocks A and B of Fig. 1, and E of Fig. 2, the energy transformer 20 is connected across the center of the block. In blocks D of Fig. 2 the energy transformer 20 is located at the right hand end of the block. The purpose of placing the energy transformer in the center of the block is to reduce the losses due to resistance and reactance, which of course is not important in short blocks like D.

Situated at each end of the blocks A, B, of Fig. 1, and E of Fig. 2, is a signal controlling device 25. Such signal controlling device is constructed as a polyphase motor with two stator coils 26-27 and a rotor coil 28. The coil 26 is in series with the secondary 29 of a transformer 30. The primary of this transformer is formed of two coils 31-32. The terminals of the coil 31 are connected at a distance apart to the track 7, and the terminals of the coil 32 are connected at a distance apart to the track 8. By separating the terminals of the coils at their points of connection to the respective tracks, a definite difference of potential will exist between the terminals of each coil, and these two differences of potential will be added together, and the primary, made up of the coils 31-32 of the transformer 30 will be excited by the added difference of potential. The coil 27 is in series with the secondary coil 33 of transformer 34, whose primary is connected through one terminal to the rail 7, and through the other terminal to the rail 8. By reason of the arrangement of the transformers 30 and 34, as above described,

the potential of the signaling current impressed upon the track rail by the transformer 20 is stepped up in the coils 26-27. The difference of potential in the coils 26-27 5 may be the same or different, as desired. It will be understood, that the current traversing the coil 26, acting in conjunction with coil 27, will produce rotary movement of the coil 28 and thereby operate the signal controlling device 25 to control the local circuit and the signal in such circuit.

10 The rotor coil 28 of each signal controlling device is provided with an arm 36, adapted to coact with contact plate 37 to control a local circuit 38, including a signaling device 39 and battery 40.

15 In the short blocks D (Fig. 2) the signal controlling device 25 has the stator coil 27 connected as in Fig. 1, and the stator coil 26 20 connected in series with the secondary of a transformer 41, whose primary 42 is connected across the feeders 16-17.

25 I have not shown in the circuits of the various transformers, either reactance or resistance fixed or adjustable. It will of course be understood by those to whom this specification is addressed, that such reactance and resistance may be employed for determining the phase of the currents excited in the stator coils, etc. Such illustrative matter has been left out of the present case in order to avoid needlessly complicating the drawings.

30 In the figures the bonds 9 are shown as 35 non-inductive bonds. Manifestly there could be substituted inductive bonds of any known type. Under ordinary conditions of practice, non-inductive bonds will serve the purpose of segregating the blocks, if care is 40 taken to properly locate the signal controlling devices. In some localities, particularly where the blocks are very short and it is desired to use two signal controlling devices in series, as shown in Fig. 1, 45 it is often advisable to use the inductance crossbonds. I have not shown such type of bonds as they are well known in the art, and such illustration would not convey anything new.

50 Where short blocks are coupled to long blocks, as shown in Fig. 2, and the blocks segregated by insulation, the type of cross-bond is immaterial, and a non-inductive bond will serve the purpose. Where, however, 55 the insulation between the rails is not used, which is a possible condition, inductance crossbonds 41 should be substituted for the non-inductive bonds, the tap being from the center point as shown in left hand block 60 D (Fig. 2).

65 The operation of a system having the general features illustrated and described, is now so well understood, that it is not considered necessary to make any specific reference thereto.

Having thus described my invention, I claim:

1. In a system of automatic block signaling, a source of signaling current, a trackway divided into block sections, means for impressing signaling current upon the block sections, a signal controlling device located at each end of each block section, each signal controlling device consisting of a polyphase motor having stator coils and a rotor 75 coil; one of said stator coils energized by a current due to the added difference in potential between the terminals of two coils, one of said coils having its terminals connected at a distance apart to one rail and the other of said coils having its terminals connected at a distance apart to the other rail of the trackway, and the other of said stator coils by the difference in potential between the terminals of a coil, one terminal 80 of which is connected to one rail and the other terminal to the opposite rail of the trackway, a signal, and a local circuit controlled by both signal controlling devices.

2. In a system of automatic block signaling, a source of signaling current, a trackway divided into block sections, means for impressing signaling current upon the block sections, means for stepping up the signaling current at each end of each block section, a signal controlling device located at each end of each block section, each signal controlling device consisting of a polyphase motor having stator coils and a rotor coil; one of said stator coils energized by a current 90 due to the added difference in potential between the terminals of two coils, one of said coils having its terminals connected at a distance apart to one rail and the other of said coils having its terminals connected 95 at a distance apart to the other rail of the trackway, and the other of said stator coils by the difference in potential between the terminals of a coil, one terminal of which is connected to one rail and the other terminal to the opposite rail of the trackway, a signal and a local circuit controlled 100 by both signal controlling devices.

3. In a system of automatic block signaling, a source of signaling current, a trackway divided into block sections, means for impressing signaling current upon the block sections, two step-up transformers at each of the block sections, one of each pair of said transformers having its primary divided into two sections and such sections respectively connected to shunt to short lengths of opposite rails and one of each pair of transformers having its primary connected across the rails, signal controlling 115 devices located at each end of the block sections, each of said signal controlling devices consisting of a polyphase motor having stator coils and a rotor coil, one of such stator coils connected across the secondary 120 125 130

of the first named transformer and the other of said stator coils connected across the secondary of the second named transformer, and a local circuit and a signal in the local 5 circuit controlled by said signal controlling devices.

4. In a system of automatic block signaling, a source of signaling current, a trackway divided into block sections, means for impressing signaling current upon the block sections connected across the center of each block section, a signal controlling device located at each end of each block section, each signal controlling device consisting of a 10 polyphase motor having stator coils and a rotor coil; one of said stator coils energized by a current due to the added difference in potential between the terminals of two coils, one of said coils having its terminals connected at a distance apart to one rail and the other of said coils having its terminals connected at a distance apart to the other rail of the trackway, and the other of said stator coils by the difference in potential between 15 the terminals of a coil, one terminal of which is connected to one rail and the other terminal to the opposite rail of the trackway, a signal and a local circuit controlled by both signal controlling devices.

5. In a system of automatic block signaling, a source of propulsion current, a feeder conductor, track rails divided into block sections and conductively continuous for all currents, a source of signaling current, 20 means for impressing signaling current upon each block section, signal controlling devices located at each end of each block section, each of the signal controlling devices consisting of a polyphase motor having stator coils and a rotor coil; one of said stator coils energized by a current due to the added difference in potential between the terminals of two coils, one of said coils having its terminals connected at a distance 25 apart to one rail and the other of said coils having its terminals connected at a distance apart to the other rail of the trackway, and the other of said stator coils by the difference in potential between the terminals of a coil, one terminal of which is connected to one rail and the other terminal to the opposite rail of the trackway, a signal, and a local circuit controlled by both signal controlling devices.

6. In a system of automatic block signaling, the combination of a source of propulsion current, a trackway of which the rails are continuous for all currents, bonds dividing the trackway into block sections, 30 means for impressing signaling current upon each of the block sections, two transformers at each end of each block section, one of said transformers having its primary formed of two coils, one of said coils connected in shunt to one rail and the other of said coils

connected in shunt to the other rail, and the other transformer having its primary connected through its opposite terminals to opposite rails, signal controlling devices at each end of the block sections, each of such signal 35 controlling devices having two stator coils and a rotor coil; one of said stator coils energized by the current in the secondary of said first named transformer and the other of said coils energized by the current 70 in the secondary of said second named transformer, a signal, and a local circuit controlled by both signal controlling devices.

7. In a system of automatic block signaling, the combination of track rails, a local 40 circuit, a signal in the local circuit, and a signal controlling device; said signal controlling device having stator coils and a rotor coil, one of said stator coils connected in series with the primary of a transformer, 80 said transformer having two primary coils, one of said primary coils having its terminals connected a distance apart to one rail of the trackway, and the other primary having its terminals connected a distance apart 85 to the other rail of the trackway, and said primaries wound to produce an added difference of potential, and the other stator coil connected in series to the secondary of a transformer having the terminals of its primary connected one to one rail and the other to the other rail, said signal controlling device adapted to control the local circuit and the signal therein.

8. In a system of automatic block signaling, a source of signaling current, a trackway divided into block sections, means for impressing the signaling current upon the block sections, signal controlling devices located at each end of the block sections, each 100 of said signal controlling devices consisting of a polyphase motor having stator coils and a rotor coil, a transformer having its primary connected across the track rails and its secondary across one of the stator coils, 105 a transformer having its primary divided into two coils, one of said coils connected a distance apart along one track rail and the other coil connected a distance apart along the opposite track rail and said coils wound 110 in the same direction, and its secondary connected to the other stator coil, a signal, 115 and a local circuit controlled by both signal controlling devices.

9. In a block signaling system, in combination with an electric railroad having both rails conductively continuous for all currents, sources of alternating current connected across the rails at intervals, bonds connected across the rails at points between 120 said courses, two transformers located at each end of said block sections and between the bonds of the block sections, each of said transformers having magnetic cores, one of said transformers having a plurality of pri- 125

mary coils thereon, one of said coils being connected through its terminals at a distance apart to one rail, and the other of the coils being connected through its terminals 5 at a distance apart to the other rail; and the other transformer connected through its terminals, one terminal to one rail and the other terminal to the opposite rail, signal controlling devices at each end of each 10 block section, each of said signal controlling devices normally energized by the collective

action of the secondary currents from the two transformers, a signal, and a local circuit controlled by both signal controlling devices.

15 In testimony whereof, I affix my signature in the presence of two witnesses.

GEORGE HILLARD BENJAMIN.
